[57] CLAIM

The ornamental design for a container for burnable insect coils, as shown and described.

DESCRIPTION

FIG. 1 is a perspective view of a container for burnable insect coils, showing our new design, the rear, left and right sides being identical thereto;

FIG. 2 is a front elevational view thereof;

FIG. 3 is a top plan view thereof; and,

FIG. 4 is a bottom plan view thereof.

The broken line showing of environment in FIGS. 1-3 is for illustrative purposes only and forms no part of the claimed design.
